UNITED STATES PATENT OFFICE.

WALDEMAR KOPS, OF NEW YORK, N. Y., ASSIGNOR TO KOPS BROS. INC., OF NEW YORK,
N. Y., A CORPORATION OF NEW YORK.

APPAREL GARMENT.

Application filed January 21, 1928. Serial No. 248,307.

My present invention relates to an apparel garment and more particularly to that type of undergarment known as a girdle. The object of the invention is the construction of the 5 upper front portion of the garment to control the action of the diaphragm and the flesh adjacent the same of the wearer.

The garment is constructed to perform its intended function and preferably extends 10 from approximately the waist line, or slightly above the same, to a line below the hips, and includes a front member and a back member, both of which are preferably made of inelastic material, together with side members 15 of elastic material, all of which are permanently connected so that the garment, furthermore, is of the step-in type. The front member of the girdle is made to include a central section which preferably has 20 oppositely disposed sides diverging upwardly and connected to lateral sections of the front member. Between the central section of the front member and the forward portions of the side members I employ additional straps 25 which are made of elastic material and are placed so as to extend over the upper portions of the elastic sections of the side members and over the upper portions of the lateral sections of the front member to co-act with 30 the elastic sections of the side members and the central section of the front member to provide an additional tension over the dia- 35 phragm of the wearer to control the same and the flesh at this portion of the body.

In the drawing Figure 1 is a perspective view illustrating the use of a garment made in accordance with this invention,

Fig. 2 is an enlarged elevation of the back of the garment, and

Fig. 3 is an enlarged elevation of the front of the garment.

By reference to the drawing it will be seen that in carrying out the invention the front member of the garment includes a central section 10 and lateral sections 11 and 12. The sides of the central section 10 preferably diverge upwardly from the bottom to the top edge of the garment. One edge of this central section 10 is connected to the lateral section 11 by a reinforcing strip 13 and suitable lines of stitching. Similarly the other edge of the central section 10 is connected to the adjacent edge of the section 12 by a reinforcing strip 14 and suitable lines of stitching,

55 In a centrally disposed position extending from the upper edge of the garment the central section may be fitted with a stay 15 and the reinforcing strips 13 and 14 may include pockets for stays 16 and 17 which also extend 60 from the upper edge of the garment downwardly and as illustrated, are substantially of the same length as the stay 15. This front member of the garment is made of suitable inelastic material. The back member of the 65 garment, as indicated at 18, may be provided in suitable positions with pockets for stays, as indicated at 19, 20 and 21.

The side sections of the garment are preferably made of elastic material. The left hand side member of the garment is constructed to 70 include elastic sections 22 and 23 preferably connected at adjacent edges by means of a reinforcing strip 24 and suitable lines of stitching. The forward edge of the elastic section 22 is connected to the front section 12 in 75 a similar manner, while the rear edge of the section 23 is similarly connected to one edge of the back member 18. The right hand side member is constructed to include elastic sections 25 and 26. The adjacent edges of these 80 sections are connected by a reinforcing strip 27 and suitable lines of stitching. The forward edge of the section 25 is similarly connected to the edge of the front section 11, and the rearward edge of the elastic section 26 85 is connected in the same manner to the adjacent edge of the back member 18.

As clearly indicated in Figure 3 the reinforcing strips 24 and 27 of the side members are so placed as to lie slightly forward of 90 the axillary lines of the garment. In the upper portions of the garment I employ reinforcing members 28 and 30, the former being connected to the reinforcing strip 27 and the latter to the reinforcing strip 24. The 95 reinforcing members 28 and 30 are preferably triangular in configuration. As illustrated, these are so placed that the edge 29 of the member 28 extends downwardly from the upper edge of the garment toward the front central line thereof. Similarly the edge 31 of the member 30 inclines in the opposite direction from the upper edge of the garment toward the front central line thereof. The garment also includes the tension straps 32 100 and 33 which are of suitable elastic fabric. The forward edge of the tension strap 32 is connected to the reinforcing strip 13 by the 105

same lines of stitching that connect this reinforcing strip and the sections 10 and 11. The opposite end of the tension strap 32 is connected to the forward edge of the member 5 28. Similarly the tension strap 33 at its forward edge is connected to the reinforcing strip 14 by the same lines of stitching which connect this reinforcing strip and the sections 10 and 12 while the opposite and rearward to 10 edge of the tension strap 33 is connected to the inclined edge 31 of the member 30. The edge portions of the central section 10 diverge in such a manner that the edges 29 and 31 of the members 28 and 30 are so inclined to 15 that they are substantially parallel therewith. The tension straps 32 and 33 are substantially rectangular and consequently when connected in the garment incline downwardly from the front central section 10 of 20 the front member toward the axillary portion of the garment. In so doing these tension straps overlie parts of the upper portions of the elastic sections 22 and 25, and also parts of the upper portions of the lateral sections 11 and 12.

It will now be understood that the circumferential tension created by the elastic side members causes the upper portion of the front member to exert a given pressure over 30 the diaphragm and this pressure extends entirely across the upper portion of the front member while simultaneously the tension straps 32 and 33 cause an additional tension to be applied to the upper portion of the central section of the front member which 35 tension obviously extends across the portions of the garment covered by these tension straps. The tension exerted by the tension straps is in a slightly downward direction 40 while that exerted by the elastic sections of the side members is in a circumferential direction. These co-acting tensions function to reduce and control the flesh of the body over the diaphragm.

45 Furthermore, as illustrated the garment may be fitted with suitable hose supporters. The hose supporters at the lower front portion of the garment are indicated at 34 and 35, those at the sides of the garment are indicated at 36 and 37, and those at the lower portions at the back of the garment are indicated at 38 and 39.

I claim as my invention:

50 1. In a garment of the type described, a front member, a back member, side members, the said members having elastic sections for-

ward of the axillary line forming a girdle adapted to extend from approximately the waist line downwardly over the thighs, tension straps in the upper front portions of the 60 garment extending over parts of the elastic side members and parts of the front member and having their forward ends connected in spaced positions to the front member, to provide a laterally downward tension co-acting 65 with the tension exerted circumferentially by the elastic side members for controlling the diaphragm of the wearer.

2. In a garment of the type described, a front member of inelastic material comprising central and lateral sections, a back member of inelastic material, side members having sections of elastic material immediately forward of the axillary line, and tension straps extending downwardly from the upper edge portion of the central section of the front member toward the axillary portions of the garment and overlying an upper portion of the lateral sections of the front member and upper parts of the sections of elastic 80 material of the side members for creating a laterally downward tension co-acting with the circumferential tension provided by the elastic sections of the side members for controlling the diaphragm of the wearer. 85

3. In a garment of the type described, a front member of inelastic material comprising a central section having upwardly diverging edges and lateral sections connected thereto, a back member of inelastic material, side members each including sections of elastic material connected by reinforcing strips which lie appreciably forward of the axillary lines of the garment, reinforcing members overlying parts of the forward elastic sections of the side members adjacent the said reinforcing strips, and tension straps of elastic material extending downwardly from the upper edge portions of the central section of the front member, overlying upper 100 portions of the said lateral sections of the front member and parts of the upper portions of the said elastic sections of the side members, and connected, to the forward edges of the said reinforcing members to exert a laterally downward tension co-acting 105 with the circumferential tension provided by the elastic sections of the side members for controlling the diaphragm of the wearer.

Signed by me this 7th day of January, 1928. 110

WALDEMAR KOPS.
